United States Patent

Des. 242,443

Patented Nov. 23, 1976

242,443

SPROCKET

John C. McGregor, Sr., 252 N. Broadmoor Blvd., Daniel P. McGregor, 1505 N. Lowry Ave., and James B. McGregor, 622 Snowhill Blvd., all of Springfield, Ohio 45504

Filed June 9, 1975, Ser. No. 585,336

Term of patent 14 years

Int. Cl. D12—11

U.S. Cl. D12—123

FIG-1

FIG-2

FIG-3

FIG-4

FIG-5

FIG. 1 is a perspective view of the sprocket embodying our new design;

FIG. 2 is a front elevation view thereof;

FIG. 3 is a rear elevation view thereof;

FIG. 4 is a side elevation view thereof; and

FIG. 5 is a fragmentary sectional view thereof taken on line 5—5 of FIG. 3.

We claim:

The ornamental design for a sprocket, as shown.
